(57) **CLAIM**

The ornamental design for an electrical connector, as shown and described.

DESCRIPTION

FIG. 1 is a perspective view of an electrical connector showing our new design;

FIG. 2 is a front elevation view thereof;

FIG. 3 is a right side view thereof, the left side view being a mirror image thereto;

FIG. 4 is a top plan view thereof;

FIG. 5 is a bottom plan view thereof; and,

FIG. 6 is a cross sectional view thereof, taken along line "6—6" in FIG. 2.
